UNITED STATES PATENT OFFICE.

ALPHEUS W. ALTORFER, OF PEORIA, ILLINOIS, ASSIGNOR TO ALTORFER BROS. COMPANY, OF EAST PEORIA, ILLINOIS, A CORPORATION OF ILLINOIS.

WASHING MACHINE.

Application filed December 12, 1923. Serial No. 680,163.

To all whom it may concern:

Be it known that I, ALPHEUS W. ALTORFER, a citizen of the United States, a resident of Peoria, in the county of Peoria and State of Illinois, have invented new and useful Improvements in Washing Machines, of which the following is a specification.

This invention has reference to washing machines and particularly to that type of machine intended for domestic or household use, and it has for its principal object to improve that type of vacuum cup machines which provide some means for reciprocating the shaft on which the cups are mounted, and which also provide a means for displacing the cups during such reciprocation of the shaft, whereby the cups may be brought into contact with all portions of the clothes and other materials during the successive reciprocations of the shaft.

In the development of this type of machine Schoregge, Patent No. 825,939 dated July 17, 1906, discloses a reciprocally arranged shaft passing up through the bottom of the tub or container and rotatable loosely thereon is a collar having radially arranged cup supporting arms from the ends of which depend cups so shaped that the water acting thereon will tend to push or impel the cups and cause the same, together with their supporting arms and collar, to be revolved about the shaft. This, in effect, gives an impositive movement to the cups so in case the clothes within the tub or container becomes wrapped around the shaft, such resistance will overcome the action of the water on the cups, with the result that the cups and supporting arms will not be rotated, although the shaft may continue to be reciprocated. The cups will again resume their rotary movement when such resistance is removed.

Zuill, Patent No. 1,021,498 dated March 26, 1912, discloses a reciprocally arranged shaft passing up through the bottom of the machine with cups suspended from arms connected with the upper end of said shaft. Zuill provides a ratchet and pawl mechanism for imparting a step by step movement to the shaft for intermittently rotating the shaft and cups, as the shaft is reciprocated, so as to bring the cups into contact with all portions of the clothes during each complete rotation of the shaft. Wrapping and en-

tangling of the clothes is common in machines of this type and cannot be prevented. 55

Adams, Patent No. 1,406,137 dated February 7, 1922, discloses a reciprocally arranged carrier to the upper end of which are carried arms from which depend the cups. He provided an impositive movement 60 for rotating the carrier and cups, in the form of clutch members, one of which he designated a piston and the other a sleeve. The piston connected with the lower end of the carrier and the sleeve encircling the carrier and having an annular slot engaging a fixed pin. A yielding means such as a spring bearing on the upper end of the sleeve to exert the necessary pressure to cause sleeve and piston to have the required impinging relation to rotate the carrier and cups when the piston and sleeve are raised and turned through the action of the pin in the slot of the sleeve. In the event clothes within the tub become wrapped around the carrier, or otherwise become entangled, such resistance will overcome the pressure of the spring, with the result that the clutch will slip and the carrier and cups will not be rotated. 70 When such resistance is removed the clutch members will automatically act to impart a rotary movement to the carrier and cups. 75

Craver, Patent Nos. 1,456,052 and 1,456,053 dated May 22, 1923, disclose a further development and wherein a vertically disposed 80 reciprocal shaft extends through the bottom of the tub and an impositive connection, in the form of clutch members is provided between the shaft and the driving mechanism. The cups being carried by arms connected to the upper end of the shaft are compelled, at all times, to rotate with the shaft when the clutch members act to impart rotary movement to the shaft. The clutch members in this arrangement are included in the supporting means for the shaft, and the arrangement of the clutch members is such that if the clothes should become wrapped around the shaft, or if for any other reason the rotary movement of the cups is opposed to an unusual degree they will stop rotating until the opposition ceases. In all such impositive drives for rotating the cups they operate substantially silently, avoiding the click present in ratchet and pawl type machines. 85 90 95 100 105

From the foregoing it is apparent, that with the exception of Schoregge, the types disclosed each rotate the shaft to impart rotary movement to the cups and Schoregge 5 rotates his cups around the shaft caused by pressure exerted by the water upon peculiarly shaped cups. Each of the impositive driving types referred to have the same faulty construction and that is the drive for 10 the cups is located at a point removed from the point where the application of power should be made.

In my improved construction the cup supporting shaft is carried up through the bottom 15 of the tub and the mechanism which imparts reciprocal movement thereto is also arranged to alternately rock the shaft back and forth during each reciprocation of said shaft; the rocking of the shaft in one direction being perceptible at or about the time the cups are lifted out of the water, and although the cup supporting arms are free to be rotated loosely around the upper end 20 of the shaft, the rocking of the shaft will tend to move the cups around therewith, the distance of travel of the cups depending on 25 working conditions within the tub. On the downward stroke of the shaft, the reverse rocking movement imparted thereto will tend to kick the shaft away from the cups and even though there may be a slight kick 30 back of the cups, said cups will enter the water and be held against any rotary movement during the pounding action. Thus as the shaft is reciprocated and rocked back 35 and forth the cups will be impositively rotated so as to bring the cups into contact with all portions of the clothes during the washing operation. Such construction, also 40 presents the advantage that if the clothes should become wrapped around the shaft or if for any other reason the rotary movement of the cups is opposed they will stop 45 rotating until the opposition ceases. Furthermore, the attendant may stop the rotary movement of the cups, at will, or spin the arms on the shaft without any danger of 50 disarrangement of parts or stopping the reciprocation and rocking of the shaft or the mechanism for actuating the same. With 55 my improved structure for impositively rotating the cups I do away with all clutch members, thereby simplifying the structure and reducing the cost and the arms may be arranged so that they are removable from 60 the shaft. Furthermore, I am enabled to time the rotation of the cups so that such rotation may occur at or about the time the cups leave the water and thus insure the 65 displacing of the cups just before the downward or pounding movement starts and not be forced to rely on a movement which may depend for its action on gravity or the application of spring pressure such as is the case in the patents referred to.

Other objects and aims will more fully appear, such as an evening device for leveling the machine when standing on an uneven floor and to a switch means for controlling the source of power to the motor.

70

That the invention may be more fully understood, reference is had to the accompanying drawings, illustrating a preferred embodiment of the invention, in which:-

Figure 1 is an elevation partly broken 75 away and partly in section showing a vacuum washing machine embodying my invention;

Figure 2 is a plan view partly in section showing the mechanism and machine parts 80 located immediately below the tub;

Figure 3 is a sectional detail as the same would appear on the line 3—3 Figure 2;

Figure 4 is a cross-section as the same would appear on the line 4—4 Figure 3; 85

Figure 5 is a detail of shifting means as the same would appear on the line 5—5 Figure 2;

Figure 6 is an enlarged detail view of the mechanism for reciprocating and rocking 90 the cup shaft, the shaft shown in its lowermost position;

Figure 7 is a view similar to Figure 6 except that the shaft is shown in its uppermost position and the operating mechanism 95 correspondingly located;

Figure 8 is a cross-section, in plan, as the same would appear on the line 8—8 Figure 6;

Figure 9 is a cross-section, in plan, as the 100 same would appear on the line 9—9 Figure 7;

Figure 10 is a detail in elevation, partly in section, of parts as they would appear on the line 10—10 Figure 6 looking in the 105 direction of the arrows;

Figure 11 is a detail of spring and cage therefor as the same would appear on the line 11—11 Figure 7;

Figure 12 is an enlarged detail in plan of 110 the cup supporting arms and the hub ring by means of which said arms may be fitted to the upper end of the reciprocating and rocking shaft;

Figure 13 is an enlarged detail in elevation, partly in section, showing the manner of attaching the cup supporting arms to be moved freely around the shaft and the means permitting detachment of the arms from said shaft; 115

Figure 14 is a vertical sectional detail as the same would appear on the line 14—14 Figure 13;

Figure 15 is a sectional detail as the same would appear on the line 15—15 Figure 12; 125

Figure 16 is a view in elevation showing an evening mechanism arranged to automatically level the machine on an uneven floor;

Figure 17 is a plan view of a base for 130

a machine and my evening mechanism therefore, as the same would appear on the line 17—17 Figure 16;

Figure 18 is a detail in plan, partly in 5 section showing a caster and evener connection;

Figure 19 is a detail in cross-section as the same would appear on the line 19—19 Figure 18;

10 Figure 20 is a side elevation of the machine, in dotted lines and in full lines showing the switch control rod and connection;

Figure 21 is a detail of the switch control shown in Figure 20 and applied to 15 what may be termed a knife switch, and

Figure 22 shows the switch control modified to adapt it to a ratchet and pawl switch.

Like characters of reference denote corresponding parts throughout the figures.

In the drawings, the washing machine is shown including a tub or container 1, supported by legs or standards 2, each having a caster-wheel 3. One or more of the legs 25 or standards have connected thereto caster-wheels, between which is arranged an evener mechanism, to be more fully described, for automatically leveling the machine on an uneven floor. The tub or container is supported on a base ring 4 and is provided with a removable lid or cover 5.

Passing up through the base ring and bottom wall of the tub is a reciprocal and rockable shaft 6, a suitable sleeve structure 35 7 for the shaft upstanding within the tub and having suitable packings at both ends to prevent leakage around its lower end and through the bottom of the tub and at its upper end around the shaft into the upstanding sleeve. To said shaft, at or near its lower end is secured a collar 8. The pin 9 used for connecting said collar to the shaft extending out from one side thereof, a suitable distance. Below the collar 8 and 40 preferably on the lower end of the shaft is held a sleeve 10 and extending diametrically from opposite sides of said sleeve are trunnions 11 forming or providing a fulcrum for opposite members 12 of a link 13. The opposite ends of the members 12 being 45 connected by a rod 14 which also connects the forward end of a lever 15 with said link. Said lever extends to one side of the machine and is pivoted thereto, at 16 and at 50 its forward end is provided with a projection 17 to which is connected and upstands, at a slight inclination, a finger bar 18 having an opening 19 therethrough, at its upper end through which projects the 55 pin 9, previously referred to. The opening 19 in the finger bar 18 is comparatively larger than the pin 9, as shown for purposes to be explained.

60 The mechanism for oscillating the lever 15 is best seen in Figures 1 and 2 and

comprises a prime mover 20, preferably in the form of an electric motor, to the shaft of which is connected a pulley wheel 21 operating a belt 22 which in turn actuates a pulley wheel 23 on a shaft 24. This shaft 70 is geared by gear wheels 25 and 26 to a two part counter-shaft 27 and 27^a, the latter section having connected to one end a crank arm 28 which in turn is pivotally connected to a pitman-bar 29 also connected to the 75 lever 15 midway its ends, as shown. Thus it will be observed that when the motor 20 is running motion will be imparted to the two part shaft 27 and 27^a through the gearing described, shaft 24 and belt 22 which 80 will reciprocate the pitman bar 29 and oscillate the lever 15 up and down and through said lever, the finger bar 18 and connections to the shaft 6 through the pin 9 will impart a reciprocal and rocking movement to said 85 shaft. Although forming no part of the present invention, the shaft section 27 is provided with a bevel gear wheel 30 meshing with a bevel gear wheel 31 on an upstanding wringer shaft 32 through and by 90 means of which motion may be imparted to the wringer mechanism 33 partially shown in Figure 1. The shaft sections 27 and 27^a are arranged with clutch members 34 and 34^a respectively, the former having a spline 95 and groove connection with the shaft section 27 to slide thereon and to be moved into and out of clutch engagement with the other clutch member 34^a. Such movement is accomplished through a yoke 35 100 engaging the clutch member 34 to which is connected a lever arm 36 pivoted at 37 and to the forward end of said lever arm is connected a cross shifting bar 38 which extends out to one side of the machine and 105 has coupled thereto an operator's rod 39 arranged in an upstanding position on the outside of the tub, see Figures 2 and 20.

On examination of Figures 1, 2, 6 and 7 it will be noted that suitable supports and casings are provided for the motor, gearing, shafts and other elements constituting the operating mechanism for imparting a reciprocal and rocking movement to the shaft 6, but as to their specific character we 110 are not here concerned, as they may be of any design or character suitable to accomplish the results herein aimed at. It may be found desirable to provide a belt tightener so I have shown an idler wheel 40 115 bearing against the belt 22 and carried by an arm 41 pivotally connected to the base ring 4, see Figure 1.

Referring to the cup structure, supporting arms and means for connecting the 120 same to the upper end of the shaft 6 to be reciprocated thereby, free to be turned thereon and to be rotated as the shaft 6 is rocked, attention is directed to Figures 1, 125 12, 13 and 14. To the upper end of the 130

shaft 6 is secured a grooved collar 42 preferably rather shallow in depth and therefore provided with a very narrow base flange 43. On this collar 42 is carried the 5 hub ring 44 from which extend the spaced radially arranged cup supporting arms 45, of which there are preferably three, although two could be used, if desired. Said hub ring is designed to have rather a snug 10 fit around the collar 42 and to rest on the narrow flange 43 and may be swung around, at the will of the attendant using the machine to displace the cups when inserting or removing clothes or for any other reason. 15 The flange 43 of the grooved collar although very narrow presents an equal bearing around the underside of the hub ring of the cup supporting arms and facilitates in 20 equalizing the lifting of the cups and arms as the shaft is raised and prevents canting of the arms. Bearing in mind that there is a vacuum formed within the cups as they 25 reach the surface of the water and the pull is against the suction created thereby an equalized lift is desirable to prevent any 30 canting which may be caused by an uneven water line due in part to agitation which might prevent all cups leaving the water at the same time. Provision is made to 35 removably attach the hub ring and arms to the grooved collar and comprises a tubular boss 46 extending radially from the hub ring 44 between two of the arms 45 and the end of said boss is provided with a trans- 40 verse slot 47. Extending through the boss 46 is a plunger rod 48 on the inner end of which is carried an anti-friction roller 49 insertable into and retractable from the groove in the collar 42 and on the outer end 45 of said rod is a knob 50 for operating the rod and passing through the rod is a pin 51 50 slideable in the slot 47. A spring 52 disposed within the boss 46 and around the rod 48 normally holds the roller 49 in the groove of the collar 42 with the locking pin 51 within 55 the slot 47. To remove the hub ring 44 and cup supporting arms from the collar 42 the attendant will grasp the knob 50 and withdraw the rod 48 which will remove the roller 60 from the grooved collar 42 and also the locking pin 51 from the slot 47 and upon turning the rod 48 and placing the pin 51 cross-wise of the slot 47 and against the end of the boss, as shown in dotted lines in Figure 12, the hub ring and arms may be 65 removed and replaced and again locked in position by simply turning the rod so that the pin 51 will coincide with the slot 47 and permit the spring 52 to act to push the roller 70 into locking relation with the grooved collar.

From the outer end of each arm 45 depends or is suspended a vacuum cup 52 having a yieldable connection with its arm so 75 that when the cups are lowered and engage

with an obstruction, such as clothes or other materials which may be in a more compact mass at one point and not at another, the cups may have a full pounding action and equalize themselves to the different conditions within the tub and without unequal pressure and without disturbing or displacing any of the cup reciprocating and rocking means. The preferred structure comprises a cup 52 having connected thereto an open 80 ended sleeve 53 provided with a chamber 54 where it unites with the cup and in the wall of said chamber are provided air and water exit openings 55 and the wall of the cup within the chamber is provided with air and 85 water exit openings 56 normally covered by a plate valve 57 lying loosely within said chamber and over said last mentioned openings. Each arm 45 is preferably provided with a depending open ended sleeve 58 into 90 which telescopes a sleeve 53 and extending through both sleeves and fastened to 53 is a rod 59 encircling which is a coil spring 60 to yieldingly hold the cup in normal position. Such spring will yield to allow the 95 cup to adjust itself as explained, and a second spring 61 on the outer end of the rod 59 acts as a cushion to take up the jar incident to the cup being returned to its normal position by the spring 60.

In Figure 1 the cups are shown in their uppermost position and above the normal water line, being the position of the shaft 6 reciprocating and rocking mechanism, as disclosed in Figures 1 and 7. When the shaft 100 6 is in its lowermost position, shown in Figure 6, with the cups submerged in the water within the tub, the pin 9 is approximately in the same horizontal plane with the pivot 105 16 of the lever 15 and thus it will be seen, illustrated by the dash and dot lines in Figure 6, that the shaft 6 is raised for a predetermined distance before there is any 110 perceptible rock of the shaft, but as the arc in which the outer end of the lever 15 and the pin 9 move becomes more pronounced and the pin 9 approaches the intersection of a line parallel to the axis of the shaft said 115 shaft has a very perceptible rocking movement, the pin 9 changing from the position shown in Figure 6 to the position shown in Figure 7. This movement is due both to the relation of the pin 9 and the pivot 16 of the lever 15 when the shaft 6 is in its 120 lowermost position and also the relatively large opening 19 in the finger bar 18 as compared with the pin 9. The rocking movement imparted to the shaft 6 is so timed in its relation to the lifting of the shaft that the cups are approximately at the top of the 125 water when such rocking is in full swing. In such position of the cups they are clear of any resistance the water may have against rotation of the cup supporting arms on the grooved collar 42 and therefore said arms 130

will tend to have rotative movement with and during the rocking of said shaft, but of an impositive character and not always of the same distance. In other words working 5 conditions within the tub and the presence of soap and water at the point of application of the power, to-wit the collar 42 and hub ring 44 will sometimes determine the extent of rotary movement. But whether 10 the strokes are long or short, corresponding to the forward rocking movement or not, during the washing operation and reciprocation of the shaft 6 the cups will be brought into contact with all portions of the 15 clothes or other materials. The hub ring 44 of the supporting arms being swingable on the collar 42 it is apparent that such clothes or other material become wrapped around the shaft 6 or sleeve 7 or if for any 20 reason the rotation of the cups is opposed, as the shaft 6 is rocked, the cups will stop rotating until the opposition ceases. Also the attachment of the arms 45 to the collar 42 is such that an attendant may hold them 25 against rotation or displace them without effort and without disturbing operative parts, or being compelled to rotate any of the operating mechanism when the power is off and it is desired to displace the cups, 30 without removing the same, to provide for the convenient and easy filling of the tub. On the down stroke of the shaft 6 the reverse rocking movement of the shaft starts fast and slows down as the pin 9 approaches 35 the horizontal level of the pivot 16 of the operating lever 15. In this way there is a slight tendency to a kick back of the cups but of a very limited character because the down movement of the shaft is but a short distance 40 before the cups reach the water, retarding any rotative movement of said cups, due to the rather loose connection of the supporting arms 45 on the grooved collar 42, the cups following the shaft straight down into the 45 water and pounding the clothes in the usual manner, common in machines of this character.

To insure that the shaft and cups will assume and stop in a position with the cups 50 above the water, when the power is turned off, I provide a spring 62 carried on the lower end of a rod 63 suspended from the base ring 4 at a point near the motor, such as in Figure 6 the spring 62 is compressed, and should the parts approximate this position when the power is turned off it will be readily seen that 55 the spring will act to lift the lever 15 and raise the shaft 6 and cups 52. The crank-arm 28 and pitman bar 29 may stop on dead center, which is hardly likely, but if they do, the attendant can by applying slight pressure on 60 the arm 45 turn said arms and shaft 6 a

slight distance, when spring 62 will act as indicated. Insuring the return of the cups to normal raised position access may easily be had to the clothes or other material by moving the arms 45 around on the shaft to 70 displace the cups, or the arms and cups removed as previously explained.

One of the important results obtained through the rocking of the shaft as it is reciprocated, is to obviate the danger of leakage of water through the packing or stuffing boxes for the shaft, which commonly occurs with a shaft which reciprocates only and which scores the packing. Such scoring, if any by a reciprocal and rocking shaft is 80 smoothed out by the rocking movement of the shaft.

The control means for the motor 20 comprises a switch box 65 attached to the machine at a suitable point, preferably to the 85 base ring 4 at a point near the motor, such box being wired to the motor and having a lead wire for attachment to a lamp socket. Said switch box may contain a knife switch, such as in Figure 21 to be operated 90 by a push and pull rod 66 connected with an operating arm 67 of the switch, or contain a ratchet and pawl, such as in Figure 22 to be operated by a push rod 68 connected with an operating arm 69 of the 95 switch. Both said rods would be journaled in an upstanding position on the outside of the tub and have a button 70 at their upper end to be gripped by an attendant when it is desired to operate such rods. A spring 100 71 on the rod 68 returns it to operative position after each operation. An arrangement of either of the types shown in Figures 21 and 22 provides a convenient and easy control for an attendant for stopping 105 and starting the motor.

The device for automatically leveling the machine on an uneven floor or base is best seen in Figures 16 to 18. The machine being provided with four legs or standards 2, 110 two of said legs may have casters 3 secured to their lower ends, the remaining two legs being provided with casters 3 the brackets 72 of which are preferably provided with vertically disposed sockets 73 opening out 115 of the upper ends thereof and adapted to receive and have a telescopic relation with the lower ends of the legs, as best seen in Figure 19. Also, said socketed brackets are each provided with laterally extended plates 74 and connected to said plates is a flexible strip or bar 75 to the center portion of which is secured a bracket 76 arranged to have a pivotal connection to a suitable frame part of the machine. It will thus be apparent that as the machine is moved over an uneven floor the flexible strip or bar 75 will yield allowing the socketed brackets to have a slidable relation with the legs 2 and 120 automatically level the machine. 125

The evening or equalizing means has been 5 preferably shown associated with a machine having four legs and reciprocal washing elements, and in addition to functioning as an equalizer such means as shown will absorb a part, if not all of the shock set up by the washing elements. Furthermore, such equalizing and shock absorbing may be found equally advantageous on 10 other types of washing machines.

What I claim is:—

1. In a washing machine, a container, a shaft disposed vertically through the bottom of the container, washing elements supported from the upper end of said shaft and arranged to be impositively rotated thereby, and means for reciprocating said shaft and for simultaneously rocking said shaft alternately in opposite directions. 15
2. In a washing machine, a container, a shaft disposed vertically through the bottom of the container, washing elements supported from the upper end of said shaft and arranged to be impositively rotated thereby, and means including a crank and lever connection for reciprocating said shaft and for simultaneously rocking said shaft alternately in opposite directions. 20
3. In a washing machine, a container, a shaft disposed vertically through the bottom of the container, washing elements supported from the upper end of said shaft and arranged to be impositively rotated thereby, a motor, a crank operated by said motor, and connections between said crank and shaft including a lever for reciprocating said shaft and for simultaneously rocking said shaft alternately in opposite directions. 25
4. In a washing machine, a container, a shaft disposed vertically through the bottom of the container, washing elements including a frame supported to be swung freely about the upper end of said shaft and to have an impositive rotary movement imparted thereto through said shaft, and means for reciprocating said shaft and for simultaneously rocking said shaft alternately in opposite directions. 30
5. In a washing machine, a container, a shaft disposed vertically through the bottom of the container, washing elements including a frame supported to be swung freely about the upper end of said shaft and to have an impositive rotary movement imparted thereto through said shaft, and means including a crank and lever connection for reciprocating said shaft and for simultaneously rocking said shaft alternately in opposite directions. 35
6. In a washing machine, a container, a shaft disposed vertically through the bottom of the container, washing elements including a frame supported to be swung freely about the upper end of said shaft and to have an impositive rotary movement imparted thereto through said shaft, and means including a frame supported to be swung freely about the upper end of said shaft and to have an impositive rotary movement imparted thereto through said shaft; a motor, a crank operated by said motor, and connections between said crank and shaft including a lever for reciprocating said shaft and for simultaneously rocking said shaft alternately in opposite directions. 40

impositive rotary movement imparted thereto through said shaft; a motor, a crank operated by said motor, and connections between said crank and shaft including a lever for reciprocating said shaft and for simultaneously rocking said shaft alternately in opposite directions. 70

7. In a washing machine, a container, a shaft disposed vertically through the bottom of the container, washing elements including a frame supported to be swung freely about the upper end of said shaft and to have an impositive rotary movement imparted thereto through said shaft, means for removably latching said frame to the shaft, and means for reciprocating said shaft and for simultaneously rocking said shaft alternately in opposite directions. 75

8. In a washing machine, a container, a shaft disposed vertically through the bottom of the container, a grooved collar secured to the upper end of said shaft, washing elements including a frame supported to be swung freely on said collar and to have an impositive rotary movement imparted thereto through said shaft, means complementary to the groove of the collar for removably latching said frame to said collar, and means for reciprocating said shaft and for simultaneously rocking said shaft alternately in opposite directions. 80

9. In a washing machine, a container, a shaft disposed vertically through the bottom of the container, washing elements including a frame supported to be swung freely about the upper end of said shaft and to have an impositive rotary movement imparted thereto through said shaft, and means for reciprocating said shaft and for simultaneously rocking said shaft alternately in opposite directions. 90

10. In a washing machine, a container, a shaft disposed vertically through the bottom of the container, washing elements supported from the upper end of said shaft, a lever means and connections between said lever means and said shaft for reciprocating said shaft and for simultaneously rocking said shaft alternately in opposite directions, said lever means and connections being so arranged that said shaft is reciprocated for a short distance in one direction before there is any perceptible rocking of the shaft and the rocking movement being so timed in relation to the reciprocation of the shaft that the washing elements are approximately out of the water by the time the rocking movement of the shaft is in full swing. 105

11. In a washing machine, a container, a shaft disposed vertically through the bottom of the container, washing elements in- 115

- cluding a frame supported to be swung freely about the upper end of said shaft and to have an impositive rotary movement imparted thereto through said shaft, and
- 5 means for reciprocating said shaft and for simultaneously rocking said shaft alternately in opposite directions, the timing of said rocking movement in relation to the reciprocation of said shaft in one direction is
- 10 such that the reciprocation precedes the rocking movement, whereby the cups are approximately clear of the water before the impositive rotary movement is imparted thereto.
- 15 12. In a washing machine, a container, a shaft disposed vertically through the bottom of the container, washing elements including a frame supported to be swung freely about the upper end of said shaft and
- 20 to have an impositive rotary movement imparted thereto through said shaft, an operating shaft, means controlling the operation of said shaft, a crank and lever connection with said shaft, a sleeve on the lower end of said shaft, means pivotally connecting the lever and said sleeve for imparting reciprocal movement to said shaft, a collar fast on the lower end of said shaft, a pin securing the collar to said shaft and extending
- 25 out therefrom, and a finger bar connection between said lever and said pin for imparting an alternating rocking movement to said shaft simultaneously as the shaft is reciprocated.
- 30 13. In a washing machine, a container, a shaft disposed vertically through the bottom of the container, washing elements including a frame supported to be swung freely about the upper end of said shaft and
- 35 to have an impositive rotary movement imparted thereto through said shaft, means for reciprocating said shaft and for simultaneously rocking said shaft alternately in opposite directions, and means to restore
- 40 the washing elements above the water line on the stoppage of said reciprocating and rocking means.
- 45 14. In a washing machine, a container, a shaft disposed vertically through the bottom of the container, means connected with the lower end of said shaft for reciprocating the same, a grooved collar secured to the upper end of the shaft, washing elements including a frame supported to be
- 50 swung freely about said collar, and means for removably latching said frame to said collar.
- 55 15. In a washing machine, a container, a shaft disposed vertically through the bottom of the container, means connected with the lower end of said shaft for reciprocating the same, a grooved collar secured to the upper end of the shaft and provided with a base flange, washing elements including a frame supported to be swung freely
- about said collar and above said flange, and latching means on the frame adapted to enter the groove of the collar for removably securing said frame on said collar.
- 60 16. In a washing machine, a container, a shaft disposed vertically through the bottom of the container, a collar secured to the upper end of said shaft, a frame having a hub ring fitting said collar and supported to be swung freely thereon and to have an impositive rotary movement imparted thereto through said shaft, a plurality of vacuum cups suspended from said frame, means for reciprocating said shaft, and means connected with said reciprocating means and with said shaft for imparting an alternating rocking movement to said shaft as it is reciprocated.
- 65 17. In a washing machine, a container, a shaft disposed vertically through the bottom of the container, a collar secured to the upper end of said shaft, a frame having a hub ring fitting said collar and supported to be swung freely thereon and to have an impositive rotary movement imparted thereto through said shaft, a plurality of vacuum cups suspended from said frame, an operating shaft, a crank thereon, a lever fulcrumed at one end to one side of the machine, a pitman bar connecting the crank with said lever intermediate its ends, a pivotal connection between the forward end of said lever and said shaft for reciprocating the same, and other connections between the forward end of said lever and said shaft for simultaneously rocking said shaft alternately in opposite directions as it is reciprocated.
- 70 18. In a washing machine, a container, a shaft disposed vertically through the bottom of the container, a collar secured to the upper end of said shaft, a frame having a hub ring fitting said collar and supported to be swung freely thereon and to have an impositive rotary movement imparted thereto through said shaft, a plurality of vacuum cups suspended from said frame, an operating shaft, a crank thereon, a lever fulcrumed at one end, a pitman bar connecting the crank with said lever intermediate its ends, a connection between said lever and said shaft for alternately rocking said shaft in opposite directions, and connections between said lever and said shaft for reciprocating said shaft as it is
- 75 rocked, said last mentioned connections permitting a free rocking movement of the shaft without disturbing its reciprocating means.
- 80 19. In a washing machine, a container, a shaft disposed vertically through the bottom of the container, a collar secured to the upper end of said shaft, a frame supported to be swung freely about said collar and to have an impositive rotary move-

ment imparted thereto through said shaft, means for reciprocating said shaft and for simultaneously rocking said shaft alternately in opposite directions, means on the collar for equally lifting the frame as the shaft is raised, and an equalizing means for the machine for automatically leveling the machine on an uneven floor.

20. In a washing machine, a container, elements supported to be reciprocated up and down in said container, a motor, oper-

ating connections between said motor and said elements to reciprocate the same, a switch controlling the source of power to the motor, and an operator's rod positioned alongside of and in a vertical position on said machine and arranged for operating said switch.

In witness whereof, I have hereunto affixed my hand this 8th day of December, 1923.

ALPHEUS W. ALTORFER.
